UNITED STATES PATENT OFFICE.

HENRY B. WALKER, OF LANCASTER, OHIO.

LOCKING DEVICE FOR WELL PUMPING-TOOLS.

1,317,531.

Specification of Letters Patent. Patented Sept. 30, 1919.

Application filed May 15, 1916. Serial No. 97,580.

To all whom it may concern:

Be it known that I, HENRY B. WALKER, a citizen of the United States, and resident of Lancaster, in the county of Fairfield and 5 State of Ohio, have invented a new and useful Improvement in Locking Devices for Well Pumping-Tools; and I do hereby declare the following to be a full, clear, and exact description thereof.

10 My invention relates to pump piston valves for oil or artesian wells, and more particularly to means for securing the valve cage to the piston.

15 In oil well pumping operations, a simple type of valve is used, comprising such parts as a piston barrel or tube, provided with a number of pistons, and a ball check-valve, seating on the barrel and confined in operative position by a cage or crown, the crown 20 and barrel usually being threaded to one another, and the cage being provided with means for attachment to the usual pumping cable or rods. In the pumping strokes, the cable connected to the walking beam twists 25 and untwists causing the vertically reciprocating piston to rotate, and great difficulty has been experienced in maintaining the union between the pump piston and cage, separation of these parts by unscrewing results in loss of the piston, causing considerable expense incident to the delay and recovery thereof.

30 The compactness in assembly of the parts of the valve and its close fit with the working barrel prohibits the employment of common mechanical devices for locking the parts together, and due to the excessive vibrations and twisting action in pumping, positive locking means of great durability must be 35 devised.

40 Other requisites in a device of this class are: flexibility, simplicity and cheapness in manufacture. With these objects in view, the invention consists in the construction 45 hereafter set forth.

45 In the accompanying drawing, Figure 1 is an elevation of a pump piston and valve cage showing the parts in locked position; Fig. 2 is a like view wherein the parts are 50 in unlocked position; Fig. 3 is a perspective view of a preferred form of locking member; Fig. 4 is a perspective view of the upper portion of the piston barrel showing the relation of the locking member thereto; 55 Fig. 5 is a longitudinal section of the upper portion of the piston barrel, the section be-

ing taken through the locking member, and its co-acting parts assembled in locked position; Fig. 6 is an elevational view of a portion of a pump piston showing a modification of the invention.

60 The numeral 2 indicates the usual pump piston barrel which has mounted thereon the packing cups 3 separated one from the other by collars 4 and carrying at the lower end 65 the cap 5. The barrel above the packing cups is provided with the shoulder 6, usually made in the form of a nut and serves as an abutment between which and the lower cap, the packing members are held.

70 The upper valve of the pump comprises a cage or crown 7, thread-connected as at 8 to the upper end of the barrel, and a ball valve 9 seating on the barrel and confined in operative position by the cage. The cage is 75 provided with a threaded stem 10 for attachment to the pumping cable or rods.

75 In a pump of the above description, it has been found that in pumping operations the threaded union between the crown and the 80 barrel tends to separate or unscrew, and in many instances, entire separation of the parts occurs, resulting in delay and expense in recovering the piston portion of the pump.

85 To prevent the unscrewing or separation of parts I employ a locking key 11 preferably of the form shown in Fig. 3. This key is adapted to seat in a key-way 12 formed in the upper threaded end of the 90 piston barrel 2 and to engage the valve cage in such manner as to prevent relative movement of these parts. The lower edge of the valve cage is counterbored, forming a threaded flange 13 adapted to fit over and 95 engage the upper portion 11^a of key 11 to hold it to its seat on the barrel, while at the same time permit turning and adjustment of the cage. This flange is provided with a number of notches or shoulders 14 so arranged that in the adjustment of the valve to the barrel one of these notches is brought

100 into register with the key, the lug portion 11^b engaging the notch to hold the cage against movement, the key being supported 105 in engagement with the cage by a sleeve or collar 16 threaded to the barrel and bearing against the underside of lug 11^b. This sleeve is counterbored as at 17 to permit free turning while in engagement with the lower 110 portion 11^c of the key.

115 By this arrangement, it will be seen that

the key is confined between the barrel and the flange 13 and 17 of the cage and collar; that the lug portion of the key is flush with the exterior of the valve at this point, and 5 that the crown and key are positively held against displacement.

The forces which tend to cause separation of the crown and barrel also act to cause the collar 16 to unscrew. It is important to 10 note that, these forces act only in a moderate degree on the collar by reason of the fact that the collar is not in frictional engagement with the working barrel, and it has been found in practice that a spring such 15 as a light spring 18 interposed between the nut 6 of the barrel and the collar is sufficient to prevent rotation, and flexible enough to allow backing down of the collar to allow disengagement of the key with the crown. 20 The collar may be dispensed with and the spring 18 or a split spring washer may be employed to support the key in locking engagement with the crown, but I prefer to use a collar as shown, as it serves as a supplemental lock, acting as a jam nut to the 25 crown.

In the modified form shown in Fig. 6, the collar 16 is provided with notches 20. These notches are of shallower depth than notches 30 14 formed in the flange of the valve cage, and are adapted to receive the lug portion 11^b of the key, and form with notches 14 positive locking means for the valve cage and collar.

35 What I claim is:

1. A device of the character described comprising a pump piston barrel having an upper threaded portion, a crown forming a valve-cage engaging said threaded portion, positive locking means on said threaded portion engaging said valve-cage, and a second locking means on said threaded portion for holding said valve-cage and said first locking means in locked position.

45 2. A device of the character described comprising a pump piston barrel having an upper threaded portion, a crown forming a valve-cage engaging said threaded portion, a key engaging a keyway formed in said threaded portion, said cage having a notch at the lower end thereof adapted to engage said key, and means carried by said threaded portion for retaining said key in engagement with the notch on said valve-cage.

55 3. A device of the character described comprising a pump piston barrel having an upper threaded portion, a crown forming a valve-cage engaging said threaded portion, a key engaging a vertical keyway

formed in said threaded portion, said valve-cage having a notch at the lower end thereof engaged by said key, and a collar engaging said threaded portion to hold said key in engagement with said notch. 60

4. A device of the character described 65 comprising a pump piston barrel having an upper threaded portion, a crown forming a valve-cage engaging said threaded portion, a key engaging a vertical keyway formed in said threaded portion, said key having an outwardly projecting lug adapted to engage a notch formed in the lower end of said valve-cage, and means carried by said threaded portion for holding said lug in engagement with said notch. 70

5. A device of the character described comprising a pump piston barrel having an upper threaded portion, a crown forming a valve-cage engaging said threaded portion, a key engaging a keyway formed in said 75 threaded portion, an outwardly projecting lug on said key adapted to engage a notch formed in the lower end of said valve-cage, a collar engaging said threaded portion adapted to hold said lug in engagement with 80 said notch, the lower end of said valve-cage and the upper end of said collar being counterbored to receive said key. 85

6. A device of the character described comprising a pump piston barrel having an 90 upper threaded portion, a crown forming a valve-cage engaging said threaded portion, a key engaging a key-way formed in said 95 threaded portion, a projection on said key engaging a notch formed in the lower end of said valve-cage, a collar engaging said threaded portion adapted to hold said projection in engagement with said notch, said projection being flush with said valve-cage and said collar. 100

7. A device of the character described comprising a pump piston barrel having an upper threaded portion, a crown forming a valve-cage engaging said threaded portion, a key engaging a keyway formed in said 105 threaded portion, said key engaging said valve cage, a collar on said threaded portion adapted to hold said key in engagement with said valve-cage, and an abutment on said barrel, and a spring interposed between 110 said collar and said abutment.

In testimony whereof I, the said HENRY B. WALKER, have hereunto set my hand.

HENRY B. WALKER.
